CARD TABLE TRAY

Theodore De Vaughn Alexander, Atlanta, Ga.

Application October 1, 1937, Serial No. 166,880

1 Claim. (Cl. 311—103)

This invention relates to improvements in card table trays.

The primary object of this invention is to provide a removable card table tray adapted to be fitted to the corner portions or areas of a conventional card table with a minimum effort of time and energy.

A further object of this invention is to provide a tray of the above mentioned character capable of holding glasses and articles as well as cigarettes and cigars and in addition there is provided an ash tray in close proximity to the cigarette holder.

A further object of this invention resides in the arrangement of the trays with respect to the table in that they are positioned directly to the right of the user, to be within easy reach of the player and at the same time in a location which will not interfere with the user's arms while playing bridge and other card games.

A further object of this invention is to provide novel fastening means for effecting the detachable connection between the table and tray and said connection includes a pair of prongs carried by the tray adapted to be passed through openings formed in the table top adjacent the corners so that the free ends of the prongs may extend through the table top and be anchored by means of sliding locking keys or pins.

Other objects and advantages of the invention will become apparent during the course of the following description, taken with the drawings, wherein,

Figure 1 is a top plan view of a card or bridge table illustrating a tray embodying this invention attached to each corner thereof;

Figure 2 is a top plan view of the tray substantially enlarged to illustrate the structure thereof and showing the manner in which the same is attached to one corner of the table which is shown as being partly broken away;

Figure 3 is a bottom plan view of the tray showing the various recesses for accommodating the articles to be supported as well as the prongs which are adapted to extend through the table top;

Figure 4 is a side elevational view of the tray illustrating the manner in which it is attached to the table and its general location with respect thereto;

Figure 5 is a vertical cross-sectional view of the tray illustrating the manner in which the various depressions are formed for accommodating the articles;

Figure 6 is a bottom plan view of a card table

illustrating the fastening means carried by the underside thereof;

Figure 7 is a bottom plan view of a card table showing the fastening means carried thereby and the tray associated with the corner portion 5 or area of the table;

Figure 8 is a vertical cross-sectional view of a corner area of a card table showing the manner in which the plugs carried by the tray extend therethrough and is fastened on the underside by 10 means of the sliding pins; and

Figure 9 is a vertical cross-sectional view taken at right angles to Figure 8, and further illustrating the manner in which the tray may be detachably connected to a corner area of a card 15 table.

In the drawings, wherein for the purpose of illustrating the invention and wherein like references will be employed to designate like parts throughout the same, the reference character 10 20 will generally be employed to designate a conventional bridge or card table including a wood top surface 11 covered by a sheet of suitable material such as composition or metal 12 and trimmed with a bead rail 13. Nails 14 may pass through 25 the bead rail 13 and be anchored in the surface 11 in order to anchor the marginal edges of the cover 12. Formed in the corner portions of the top 11 in diagonal relation to the table top are openings 14.

The invention comprises a utility tray 15 formed from a single blank of material 16 of substantially a sector-shaped piece of material such as metal or the like, and it will be noted that the tray 15 is arcuately recessed as at 17, having an inner wall 18 which conforms to the curved corner portion of the bridge table and an outer curved wall 19 terminating at each end in substantially vertical straight walls 20 and 21.

Adjacent the straight wall 20 of the recess 17, there is formed a circular recess 22 of a depth sufficient to receive and hold a tumbler or glass or other circular article. Adjacent the vertical wall 21 of the sector-shaped recess 17 there is formed by means of a depression 24, an ash tray 45 communicating with a curved portion 25 forming a cigarette or cigar holder.

Adjacent the inner portion of the sector-shaped blank 16 is welded a plate 26 preferably rectangular in form to the straight edge 27 of the tray 15 and said plate 26 may be fastened in place by welding or other fastening means. Rubber pads or cushioning means 27 are provided on the underside of the plate 26 and are adapted to engage the table top to prevent scratching or 55

marring of the finish thereof. It will be noted that the thickness of the plate 26 is substantially the equivalent of the distance that the trim bead 13 extends above the table top 11. This allows 5 the tray to assume an even horizontal position when fastened in place upon a table.

Formed along one edge of the plate 26 are lugs which are upstruck from the plate as at 29 and 10 are bent to extend downwardly through the openings 14 arranged diagonally in the table top 11. Suitable openings 30 are formed in the plugs 29 a distance from the plate 26 equivalent to the thickness of the table top 11 and cover 12 so that the openings will be exposed on the underside of 15 the table top 11.

15 The fastening means for the trays comprises a strip of metal 31 having its free ends looped as at 32 and return bent as at 33 for being anchored by means of screws 34. The screws 34 extend 20 into the table top 11 and retain the strip 31 in place so that the loops 32 are directly opposite the slots 14 in the table top.

Slidably mounted within the loops 32 are the 25 legs 35 of a U-shaped locking bar 36. The free ends 37 of the legs 35 are presented to the openings 14 and when the lugs 29 of the tray 15 are projected through the openings the free ends 37 of the legs 35 may engage in the openings 30 and 30 lock the tray in place. A finger piece 38 is formed on the U-shaped locking member 36 so that the free ends 37 of the legs 35 may be conveniently withdrawn or inserted in the openings 30 formed in the lugs 29. A stop member 39 is located directly in back of the finger piece 38 to prevent 35 the displacement of the U-shaped locking member 36 from the loops 32. The stop member 39 is provided with screw threads 40 and may be conveniently screwed into the table top on the underside thereof as at 11.

40 It is to be noted that the trays 15 extend in a clockwise direction from the radius of the table

top 10 in order to prevent the left elbow or forearm of the player from accidentally knocking objects or articles in an adjacent tray out of place. Since the left hand is usually the hand employed 5 for holding cards in various card games, it has been found that the construction of the above described tray is advantageous because of the fact that it does not hinder or obstruct the free use or movement of the left arm of the player.

It is to be understood also, that various changes 10 in the shape, size and arrangement of parts may be resorted to and that the form of the invention herewith shown and described is to be taken as a preferred embodiment of the same.

15 I claim:

In an article holding attachment for game tables, wherein the attachment comprises a tray for the support of articles laterally of the top of the table and wherein a tray is detachably engaged with each corner of a rectangular table top, said tray comprising a receptacle portion disposed laterally of the table top, a flat plate extension overlying the corner of the table top, a pair of spaced lugs apertured at their lower ends depending from said plate extension, said table top having slotted openings therein for the passage of said lugs and a U-shaped bolt slidably mounted on the underside of the table top with the bolt legs thereof adapted to be projected into the lug apertures for holding the tray in position 25 on the corner of the table top, a strip secured to the underside of the table top having its ends overlying the bolt legs to retain the bolt in position, a finger grip carried by the cross head of the bolt and a stop pin carried by the bottom of the table positioned for engagement by said finger piece for limiting movement of the bolt relative to the retainer portions of the strap for retaining the strap engaged with the legs of the bolt at all 30 times.

35 THEODORE DE VAUGHN ALEXANDER.
